TRANSFER MECHANISM FOR LOOMS

Application filed September 17, 1927. Serial No. 220,143.

This invention relates to transfer mechanism for automatic looms of the type wherein when the thread on a bobbin is almost exhausted, the empty or nearly empty bobbin 5 is forced out of the shuttle by a full bobbin which is forced into its place by suitable mechanism.

It has particular reference to the type of loom in which the full bobbins are carried 10 in what is known as a battery, usually of circular form, and are successively carried around into suitable position over the shuttle by the battery, and at the appropriate time are forced out of the battery and into the 15 shuttle by what is known as a transfer hammer.

Such transfer obviously must occur on the battery side of the loom but in most cases, in looms as now constructed, the feeler mechanism which feels the thread on the bobbin and determines the time of transfer is on the side of the loom opposite the battery. This feeler mechanism is passive or operates in a certain way until the feeler tip 20 indicates that the filling on the bobbin in the shuttle at the side of the loom opposite the battery is almost exhausted. When this occurs, in the terms of the trade, it indicates transfer but the transfer does not occur until the shuttle returns to the battery side of the loom where and when the nearly empty bobbin is pushed out by a full bobbin through 25 the operation of the transfer mechanism.

There are types of feelers and transfer devices all of which operate on the battery side of the loom, but these are very complicated.

As there is so much mechanism on an automatic loom it is highly desirable that this 30 should be simplified because the likelihood of failure to operate and breakage etc. is greater according to the greater number of parts.

In the type of loom to which this device is 35 applicable, a dagger on the lay beam at the appropriate time engages a bunter or transfer dog which is pivoted to a tail or arm of a transfer hammer. The force of the advancing lay beam, at such time, being transmitted through the dagger and dog, forces

the hammer down on to a full bobbin in the battery, which bobbin is crowded down on to the nearly empty bobbin in the shuttle and replaces it.

The principle of such devices is that the 55 pivoted transfer dog normally hangs down below the dagger and is only brought up into position when suitable feeler mechanism controlled by the amount of yarn on the bobbin, lifts it into position.

The principle of this device is to have the normal position of the pivoted transfer dog such that it would engage the dagger 60 at every beat up of the lay beam if it was not moved out of position by suitable mechanism.

This mechanism includes an arm which engages the shuttle binder on the side of the loom opposite the battery and is connected by means of a rod, which takes the place 70 of the well known transfer rod, to the transfer dog in such manner that whenever the shuttle enters the box on the side opposite the battery, the dog is thereby moved out of the way of the dagger.

Every time the lay beam beats up with the shuttle on the battery side, by my especially devised feeler finger and its connections to the pivoted transfer dog such dog is moved out of the way of the dagger until 80 the time arrives when the yarn on the bobbin is almost exhausted, at which time my feeler finger slips aside, and as its connections therefore fail to function, the advancing dagger on the lay beam engages the transfer dog 85 and causes the transfer hammer to replace the almost empty bobbin with a new one from the battery.

By my arrangement of cooperating parts, when my detector finger and slide are pushed 90 forward by the advancing lay beam when the finger is in contact with a bobbin on which there is sufficient filling to hold the finger in its normal position, I prefer to use such a direct connection from the slide to the 95 dog that, as the slide moves back, the nose of the dog will move down to escape the dagger. This action continues until the yarn on the bobbin has been reduced to a pre-determined point. When that point is reached, the 100

detector finger suddenly turns sideways on its pivot and as the slide does not move back, the dog is left in position to be struck a powerful blow by the dagger.

5 I directly connect the slide with the dog in such manner that when this happens, the blow is transmitted to the slide which is thrown forward enough to move the detector finger out of the shuttle so that it is not in 10 the way of the incoming full bobbin. By the time it has been brought back by the detector slide spring, the transfer has been made.

The advantages of my device are that as 15 the detector device is on the battery side of the loom it is not necessary to wait for another beat up or pick but it works instantly when its finger detects that the yarn is almost exhausted. In this way a substantial amount of waste is saved on each bobbin.

20 To still further reduce this waste to the minimum I prefer to make my finger tip of some material such as fiber and to form it with a well rounded heel on the edge towards the head of the bobbin, this heel extending 25 around so that it practically engages the wood of the bobbin when the yarn in front of it is exhausted, or so that it actually may strike one or two strands of yarn which will not prevent the whole finger from turning 30 away from the head. Beyond the heel are teeth or toes which actually engage the yarn when there is any on the bobbin, such yarn preventing the tip from swinging away from the bobbin head as it does when the yarn is 35 exhausted, the finger being so pivoted that it is kept slightly off center by a suitable stop.

If perfectly made, the smooth heel only 40 will come in contact with the wood of the bobbin but to prevent the possibility of the teeth scratching the bobbin, I prefer to use fiber or similar material rather than metal, as even a slight scratch is highly objectionable where silk, rayon or similar fine fiber 45 compositions are concerned.

In the drawings, Fig. 1 is a perspective view showing my device attached to a Draper loom so-called showing only such parts of the loom as seem necessary, and with parts 50 broken away for clearness.

Fig. 2 is a side elevation of my transfer mechanism showing the position of the parts as the lay starts to beat up.

Fig. 3 is a plan view of Fig. 2.

55 Fig. 4 is a view from the opposite side of Fig. 2 but showing the feeler in contact with a bobbin and the dog depressed.

Fig. 5 is a plan view of the feeler and slide being pushed back when in contact with a 60 full bobbin.

Fig. 6 is an enlarged plan view of the feeler finger tip.

Fig. 7 is a plan view showing the position 65 of the feeler in the slide when in contact with an empty or almost empty bobbin.

Fig. 8 is an elevation enlarged showing details of construction of the pivot of the feeler finger.

Fig. 9 is a view similar to Fig. 2 but showing the feeler finger in contact with an almost 70 empty bobbin, and the position of the parts at that time.

Fig. 10 is a view similar to Fig. 9 showing the position of the parts when the transfer hammer has just forced in a full bobbin and 75 forced out an empty bobbin.

In the drawings I show such parts of an automatic or bobbin changing loom as seem necessary for an understanding of this device.

40 represents the breast beam forming part of the frame of the loom which carries at one end, as shown, the circular battery 41 which is filled with the full bobbins 18 in the usual manner. To it is pivoted at 120 the 45 transfer hammer 20 which has the usual heads or other suitable devices 220 for forcing a full bobbin such as 18 out of the battery and pushing down through the shuttle 22 an empty bobbin or almost empty bobbin. 17. 90 This transfer hammer also has an operating arm 320 which extends downward as shown, and to this is pivoted at 420 a transfer dog 6 which automatically is held up by a tension spring 12 so that its nose 6A will normally be 95 in position so that the dagger 8 carried by the lay beam 21 would normally engage it and as its upward pivotal movement is limited by stop 112, the forward motion of the lay beam will force back arm 320 and therefore downward the head 220 if the dog 6 or its nose 6A was not moved out of the way of dagger 8.

A represents a detector bed which is usually pivoted to the breast beam at 1 and either held rigidly as by a set screw 24 or normally held down by a tension spring 19. The above parts are all substantially old.

B is a detector slide slidable in or on detector bed A in suitable ways in a direction 110 substantially perpendicular to the lay beam 21 but preferably directly in line with its forward and back movement. This slide when moved back projects and will move back or forward toward the front of the loom, and is shown as extending beyond detector bed A and as being provided with a returning spring 5 which normally pushes it 115 towards the lay beam. It also has a downwardly projecting arm 100 from which horizontally projects a slide stud 14 which passes through a loop 13 in connecting rod F to be described. There is also an adjusting screw 10 by which the position of slide B can be 120 more or less regulated.

The other end 113 of connecting rod F is pivoted at 16 to a stud on one side of dog 6 which is preferably a greater distance from the center of the hammer pivot 120 than is the center of the pivot 420 for the dog itself 125 130

so that as the dog and arm 320 move back, this connecting rod will move over a greater arc than the nose 6A as indicated by the arcs shown in Fig. 2.

At the side of the loom opposite battery 41 is a shuttle binder 26 of any usual form adapted to be pushed somewhat out when the shuttle enters the box on that side, and G represents broadly the connection between this side of the loom and dog 6. As shown, shuttle binder 26 is pivoted at 126 to lay beam 21 and against this bears an arm 25 adjustably fixed to a rod 124 which extends across the loom, being carried in suitable hangers 224 on breast beam 40 and having at its battery end an arm 11 of bifurcated form having a slot 111 into which passes a stud or roller 15 which projects from dog 6 on the opposite side from stud 16.

It will be seen that when connecting rod F is pushed toward the front of the loom, or when shuttle binder 26 is pushed in that direction by the entry of a shuttle, in either case dog 6 will be pulled down on its pivot 420 so that its nose 6A will be out of the way of dagger 8. Shuttle binder 26 will act on each alternate pick and I will now describe my detector device on the side of the battery.

C represents a detector finger pivoted at one end on pivot 101 to the end of slide B which is next to the lay beam, and this has a shoulder 102 on what I will call the inside of the loom which is the side where the heads such as 118 of the bobbins are positioned in the magazine or battery. Its free end 107 curves away from the inside or from the head of the bobbin when in position away from the center of the loom, and this end is provided on the side next such heads with a smooth, rounded heel 104, and outside of such heel, that is away from the center of the loom, there are one or more teeth 103.

This end of the feeler or detector finger C should be carefully made so that one of these teeth 103 will engage the thread such as K if there is any on the bobbin but when they come in contact with a place where there is no thread K or where it is very thin as at 170, the teeth 103 will slip away from the head 118 of the bobbin with a result to be described.

Each finger C has on the inside a shoulder 102 which by means of a coiled spring 4 is kept in adjusted contact with a stop 9 on slide B. The position of slide 9 can be regulated by a screw 109 so that as shown in Fig. 5, the contact point of finger C which is ordinarily the front and longest of the teeth 103 will engage the thread K on the bobbin and so that as the lay beam advances, this thread will prevent the finger C from doubling up or bending toward the outside of the loom and away from the bobbin head 118 but will force before it, finger C and slide B carrying with them the connecting rod F and depressing dog 6.

This occurs at every alternate pick until the amount of thread K is reduced to such a point, as indicated at 170 on the bobbin, that, as teeth 103 find nothing to stop them, heel 104 slides over with the result that slide B is not moved and dog 6 is not moved whereupon dagger 8 acts upon the nose 6A of the dog and causes a full bobbin to replace an empty bobbin in a well known manner.

The provision of slot 13 allows the detector finger to be so adjusted as to move in toward the bobbin as the yarn is unwound but so that except on the detector beat, the movement of the slide transmitted through connecting rod F will pull down the nose 6A of the dog 6 along the arc V shown in Fig. 4 from the dotted line position to the full line position, the dog pivoting on the pivot 420, and also allows of the operation of means G at the other side of the loom to pull the dog out of position on the alternate picks.

On looms where the detector mechanism is on the side opposite the battery, it is not necessary to remove the feeler tip or feeler finger from contact with the nearly empty bobbin because the transfer is not made until the shuttle returns to the battery side of the loom.

With this device however it is necessary to move the detector finger out of the way of the entering full bobbin or it would be in danger of breakage. I accomplish this by positioning the pivot point 16 of connecting rod F and slide stud 14 farther from pivot 120 of the transfer hammer than pivot point 420 of the dog and farther than the dog nose 6A from 120 so that when the dagger 8 begins to force back the dog 6, on account of the greater radius, the slide B and finger C move a greater distance than the dagger 8 moves and the free end or tip 107 is therefore pulled out of the way of the incoming full bobbin. This relation is shown by the arcs X and Y in Fig. 2.

I depend mainly however on the sudden blow struck by the dagger 8 on the nose 6A of the dog 6 when the detector finger C suddenly doubles up as shown in Figs. 1 and 7 to throw forward the detector slide B as shown by the dotted lines in Fig. 9 to the limit of the slot 13 in connecting rod F, which action moves the free end 107 of detector finger C from the position shown in Fig. 9 at 107 to that shown at 507. Before it can return, a new full bobbin is in place and when the finger C comes back, it comes back straight and the yarn on the bobbin prevents it from slipping sideways. The construction of the slide and feeler is more particularly described in the copending application filed by me Aug. 29, 1927 for bobbin transfer feeler, Serial No. 216,201.

Preferably the feeler finger C is very carefully made of hard fiber and carefully adjusted so that a line such as shown in the

long dashes 0 of Figs. 5 and 6 passing through pivot 101 in the same direction as the movement of the lay beam will pass back of the front, which should be the longest, of the teeth 103 between it and heel 104.

These parts should be so adjusted that the front end of each tooth 103 will engage some of the fine threads 180 but will not dig into the wood of the bobbin, while the following teeth are positioned slightly farther away from the bobbin so that when feeler finger C does pivot at 101 the teeth will swing away from the bobbin 17 as shown by the arcs T, S and R.

I claim:

1. The combination with a loom having a lay beam which carries a dagger, and a breast beam on one end of which is a battery for bobbins and a pivoted bobbin transfer hammer operable by and to which is pivoted a dog; of a dog spring and a dog stop in position to hold the dog in a position to be struck by the dagger when the lay beam beats up; a detector bed attached to the breast beam; a detector slide slidable therein in a direction substantially the same as the movement of the lay beam and carrying a slide stud; a slide return spring; a detector finger pivoted at one end to the slide having a shoulder on the inside and having its free end curved away therefrom towards the outside of the loom, said end having on its inside a smooth rounded heel and ending in teeth beyond said heel; an adjustable detector stop so carried by the slide as to engage said shoulder and to keep the finger normally in position in which said teeth are out of a line through the finger pivot and perpendicular to the lay beam; a detector finger return spring; a connecting rod having at one end a slot through which the slide stud passes and at its other end connected to said dog below its pivot; a shuttle binder at the end of the lay beam opposite the battery and connections between said binder and dog whereby the dog is removed from position in front of said dagger when the shuttle engages said binder.

2. The combination with a loom having a lay beam which carries a dagger, and a breast beam on one end of which is a battery for bobbins and a pivoted bobbin transfer hammer operable by and to which is pivoted a dog; of a dog spring and a dog stop in position to hold the dog in a position to be struck by the dagger when the lay beam beats up; a detector bed attached to the breast beam; a detector slide slidable therein in a direction substantially the same as the movement of the lay beam; a slide return spring; a detector finger pivoted at one end to the slide having a shoulder on the inside and having its free end curved away therefrom towards the outside of the loom, said end having on its inside a smooth rounded heel and ending in teeth beyond said heel; an adjustable detector stop

so carried by the slide as to engage said shoulder and to keep the finger normally in position in which said teeth are out of a line through the finger pivot and perpendicular to the lay beam; a detector finger return spring; a direct connection between the detector slide and the dog; and means operable when the shuttle is in the box at the end of the lay beam opposite the battery to remove the dog from position in front of said dagger.

3. The combination with a loom having a lay beam which carries a dagger, and a breast beam on one end of which is a battery for bobbins and a pivoted bobbin transfer hammer operable by and to which is pivoted a dog; of a dog spring and a dog stop in position to hold the dog in a position to be struck by the dagger when the lay beam beats up; a detector bed attached to the breast beam; a detector slide slidable therein in a direction substantially the same as the movement of the lay beam; a slide return spring; a detector finger having its free end curved towards the battery away from the center of the loom, said end having on its inside a smooth rounded heel ending in teeth beyond said heel, said finger being so pivoted to the slide that the finger is normally in position in which said teeth are out of a line through its pivot on the slide and perpendicular to the lay beam; a detector finger return spring; and a direct connection between the detector slide and the dog.

4. The combination with a loom having a lay beam which carries a dagger, and a breast beam on one end of which is a battery for bobbins and a pivoted bobbin transfer hammer operable by and to which is pivoted a dog; of a dog spring and a dog stop in position to normally hold the dog in a position to be struck by the dagger when the lay beam beats up; a detector bed attached to the breast beam; a detector slide slidable therein in a direction substantially the same as the movement of the lay beam; a slide return spring; a detector finger having at its free end a smooth rounded heel ending in teeth beyond said heel, said finger being so pivoted to the slide that the finger is normally in position in which said teeth are out of a line through its pivot on the slide and perpendicular to the lay beam; a detector finger return spring; and a direct connection between the detector slide and the dog.

5. The combination with a loom having a lay beam which carries a dagger, and a breast beam on one end of which is a battery for bobbins and a pivoted bobbin transfer hammer operable by and to which is pivoted a depending dog; of a dog spring and a dog stop in position to hold the dog in a position to be struck by the dagger when the lay beam beats up; a detector bed attached to the breast beam; a detector slide slidable therein in a

direction substantially the same as the movement of the lay beam; a slide return spring; a detector finger having at its free end a smooth rounded heel ending in teeth beyond said heel, said finger being so pivoted to the slide that the finger is normally in position in which said teeth are out of a line through its pivot on the slide and perpendicular to the lay beam; a detector finger return spring; and a direct connection between the detector slide and the dog comprising a connecting rod pivoted at one end to a pin on the dog and having at its other end a slot through which passes a pin from the slide, said pins being so positioned that a line through them passes below the pivotal point of the dog.

6. The combination with a loom having a lay beam which carries a dagger, and a breast beam on one end of which is a battery for bobbins and a pivoted bobbin transfer hammer operable by and to which is pivoted a depending dog; of a dog spring and a dog stop in position to hold the dog in a position to be struck by the dagger when the lay beam beats up; a detector bed attached to the breast beam; a detector slide slidable therein in a direction substantially the same as the movement of the lay beam; a slide return spring; a detector finger pivoted to the slide so as to engage a bobbin and to swing sideways; a detector finger return spring; and a direct connection between the detector slide and the dog comprising a connecting rod pivoted at one end to a pin on the dog and having at its other end a slot through which passes a pin from the slide, said pins being so positioned that a line through them passes below the pivotal point of the dog.

40 7. The combination with a loom having a lay beam which carries a dagger, and a breast beam on one end of which is a battery for bobbins and a pivoted bobbin transfer hammer operable by and to which is pivoted a depending dog; of a dog spring and a dog stop in position to hold the dog in a position to be struck by the dagger when the lay beam beats up; a detector bed attached to the breast beam; a detector slide slidable therein in a direction substantially the same as the movement of the lay beam; a slide return spring; a detector finger pivoted to the slide so as to engage a bobbin and to swing sideways; a detector finger return spring; and a direct connection between the detector slide and the dog of such character that when the slide moves forward it will depress the dog and when the dog is forced forward horizontally, it will move the slide forward at a faster rate.

60 8. The combination with a loom having a lay beam which carries a dagger, and a breast beam on one end of which is a battery for bobbins and a pivoted bobbin transfer hammer operable by and to which is pivoted a depending dog; of a dog spring and a dog stop

in position to hold the dog in a position to be struck by the dagger when the lay beam beats up; a detector bed attached to the breast beam; a detector slide slidable therein in a direction substantially the same as the movement of the lay beam; a slide return spring; a detector finger pivoted to the slide so as to engage a bobbin and to swing sideways; a detector finger return spring; and a direct connection between the detector slide and the dog of such character that when the slide moves forward, it will depress the dog and when the dog is struck by the bunter, there is enough yielding so that the slide is thrown forward and the detector finger is withdrawn from the shuttle sufficiently to allow a new bobbin to replace the old.
